UNITED STATES PATENT OFFICE.

PHILIP MEDART, OF ST. LOUIS, MISSOURI, ASSIGNOR OF ONE-HALF TO
WILLIAM MEDART, OF SAME PLACE.

MACHINE FOR STRAIGHTENING METAL BARS OR PIPES.

SPECIFICATION forming part of Letters Patent No. 352,652, dated November 16, 1886.

Application filed April 12, 1886. Serial No. 198,560. (No model.)

To all whom it may concern:

Be it known that I, PHILIP MEDART, of St. Louis, Missouri, have invented certain new and useful Improvements in Machines for Straightening Metal Bars or Pipes, of which the following is a specification.

The object of my invention is to provide a simple, practical, and efficient machine for the straightening of metal bars or pipes.

10 In an application for Letters Patent filed by me January 13, 1886, No. 188,418, I have shown and claimed a machine in which the endwise relation of the shaft being operated upon and the straightening-rolls is varied by the draft created by the rotation of the shaft in contact with the rolls, so that the shaft is operated upon throughout its entire length. In my present invention the shaft is caused to travel both through the straightening - rolls and 15 through the shaft carrying and rotating devices by power derived in the same way. This feature of my invention, as well as others, will appear more fully from the following description.

20 25 In the accompanying drawings, Figure 1 is a side elevation; Fig. 2, a rear view of one of the chucks, showing the driving-gears; Fig. 3, a view of the face or front of a chuck; Fig. 4, a section on the line 4 4 of Fig. 2, and Fig. 5 30 a section on the line 5 5 of Fig. 3.

A is the main frame, about the middle of which is mounted the frame or bed-plate F, which carries the straightening devices. These devices are shown as consisting of pairs of 35 straightening-rolls, two such pairs being arranged below and one above the shafting, which is indicated by dotted lines in Fig. 2. All three pairs of rollers are mounted in housings f, which may be rotated about a center to adjust the rolls relatively to the shafting. The housing carrying the upper pair of rolls may be vertically adjusted by means of a screw, as clearly shown, while the lower pairs of rolls may be adjusted toward and from each other 40 by means of a reversely-threaded screw-bar. The straightening - frame or bed - plate F is mounted upon four vertical screws provided with sprocket - wheels, on which an endless chain runs. By this means the frame is raised 45 and lowered to adapt the machine to shafting of different sizes.

This part of my invention is identical in construction with that shown in another application filed by me January 13, 1886, and numbered 55 188,418, and a more specific description is therefore unnecessary.

The details of construction are obvious and, so far as this invention is concerned, immaterial. On each side of the straightening devices I mount a sheave-chuck, the details of 60 construction of which are fully shown in the drawings, and are presently described. The chuck-head is preferably carried by a tube or hollow mandrel, upon the rear end of which a gear-wheel, K, is mounted. This gear is driven 65 by a pinion on a counter-shaft provided with an ordinary belt-pulley, as seen clearly in Fig. 1. The chuck-head is provided with four corner-plates, o, between which four radially-moving sheave-blocks operated by adjusting-screws 70 p work. Each of said blocks carries a sheave or roller, P, which is preferably formed with a grooved periphery, preferably of the shape shown in the drawings. Their faces or peripheries may also be serrated or roughened, 75 as clearly seen in Fig. 6.

So far as I am aware, I am the first to use a sheave-chuck in this class of machines. It will be obvious from the construction of this chuck that a shaft or bar gripped between the 80 sheaves will be held firmly and caused to rotate with the chuck, and yet be capable of moving endwise therein when power is applied for that purpose, the sheaves turning upon their axes and permitting this action. 85

The operation of the machine is as follows: The shafting is passed through one of the sheaves X until its end comes between the straightening-rolls, the upper pair of which is screwed down to give the desired pressure, 90 and the sheaves of the chuck X are screwed up. Power being applied to that chuck, the shafting will be positively rotated, and in its rotation in contact with the straightening-rolls a strain or draft will be created which will 95 draw the shafting through the chuck X and between the straightening-rolls. As its end emerges from the straightening-rolls it will pass between the sheaves of the chuck Y and through the hollow mandrel thereof, which 100 forms a guide and support to the end of the shafting. When the other end of the shafting

has passed out of the chuck X, the chuck Y is screwed up so as to grasp the shafting, and, being driven by power in a suitable direction, the shafting will continue to move between 5 the straightening-rolls. In this way all portions of the shafting will be properly acted upon.

The shafting may be run back and forth through the machine as often as may be desired, as the workman may apply the power to drive either chuck in either direction.

I claim as my invention—

1. The combination of a sheave-chuck in which the shafting to be straightened is secured and by which it is rotated, and the straightening and draft rolls in contact with which the shafting rotates, whereby a draft or strain is created which causes the shafting to move endwise through the sheave-chuck and 15 between the straightening-rolls.

2. The combination of the straightening and draft rolls or devices, a sheave-chuck arranged on each side thereof, and driving mechanism for rotating the sheave-chucks, substantially as and for the purpose set forth. 25

3. The combination of the straightening and draft rolls or devices, a sheave-chuck, the hollow mandrel or rotating tube on which the sheave-chuck is carried, and mechanism for driving said mandrel. 30

4. The combination of the chuck-head and the radially-adjustable sheaves.

In testimony whereof I have hereunto subscribed my name.

PHILIP MEDART.
